UNITED STATES PATENT OFFICE.

EMIL TYDEN, OF EVANSTON, ILLINOIS.

VALVE FOR FIRE-EXTINGUISHING SPRINKLER SYSTEMS.

Application filed January 29, 1924. Serial No. 689,355.

The purpose of this invention is to provide an improved construction of a main valve body and parts accessory thereto of a fire extinguishing sprinkler system. It consists in the elements and features of construction shown and described as indicated in the claims.

In the drawings:

Figure 1 is an axial section of the main valve body and immediate connections with the main supply pipe.

Figure 2 is a plan view of the main valve seat, as seen with the main valve body and valve removed from the terminal of the main supply pipe.

Figure 3 is a detail section in the plane of the section of Figure 1, showing a detail modification.

In the drawings the main valve body is shown at 10 mounted upon the terminal 11 of the main supply pipe indicated at 12. 13 indicates the pipe line leading from the outlet of the valve body to the sprinkler system. 14 is the main valve controlling the inlet from the main supply pipe to the valve body and thence to the sprinkler system. This valve is hinged at one side for swinging up from its seat at the opposite side, and for the purpose of the present invention there is provided a valve seat member 16 which is circular in its exterior outline and is clamped between the similar circular marginal portions 10^a and 11^a of the valve body 10 and supply pipe terminal 11 respectively, which are secured together, clamping the said valve seat member between them by means of bolts 15. The three parts at this clamped junction are machined for watertight fit upon each other requiring no packing between them. The valve seat member 16 is provided with suitable hinge lugs 16^a, 16^b to which the main inlet valve 14 is connected by means of corresponding hinge lugs 14^a, corresponding lugs in the two parts being connected by a hinge pintle 14^b.

For serving an auxiliary device such as an alarm operated by a water motor or by flow of water, it is necessary to provide a duct leading from a point at which it will receive water escaping from the supply pipe 12 through the terminal 11, and the main valve seat opening upon the initial opening movement of the main valve; and for this purpose an auxiliary duct 32 is formed in the valve seat member 16, leading from its inlet, which is in the plane of the valve seat,

and preferably at a point diametrically opposite the hinge pivot of the main valve, out substantially radially with respect to said valve seat, opening at the periphery of the valve seat member exposed between clamping margins 10^a and 11^a of the valve body and supply pipe terminal, said valve seat member being formed with a slightly projecting nipple, 16^c, at the position in its exposed periphery through which said duct extends. Said nipple is exteriorly threaded for coupling to it a pipe member 33 for leading to the auxiliary device which is to be served by the connection with the duct 32.

The duct 32 is controlled at its inlet by an auxiliary valve 19, which is carried by the main valve, as seen in Figure 1, said auxiliary valve being mounted directly in the main valve at the side thereof opposite the hinge line, the mounting of said valve being in such manner as to adapt it to accommodate itself to its seat, as by being mounted in a bore formed in a boss 14^d with which the main valve is provided for that purpose, the auxiliary valve having limited freedom of movement in said bore both axially and transaxially of said auxiliary valve, and in which bore it is yieldingly pressed in the direction for seating, by a spring 40, the bore in which the valve and its spring are positioned being closed water tight at the end opposite that in which the valve stands, by a screwed-in plug 41 against which the spring re-acts for yieldingly thrusting the valve to its seat.

The important function served by the construction above described as comprising the auxiliary duct leading out through the exposed periphery of the valve seat member which is clamped between the valve body and the water supply pipe terminal, is, that by reason of the fact that the valve seat member 16 is held in junction with the valve body and the water supply pipe terminal without threaded joints between any of said three parts leading into the cavities of either of them, no leakage which may occur or be observed can be attributed to the leakage which is liable to occur through any threaded junction; and the possibility of leakage is therefore limited to the seating of the auxiliary valve 19. The special importance of this arises from the well-known fact that in any structure of this general character, in which there is an auxiliary duct for like purposes for which the aux-

iliary duct in this construction is provided—
operating an alarm or the like—it is the
common experience that leakage is observed
which, in constructions involving threaded
joints extending to the source of water from
which leakage might occur, may be attributed
either to the lack of tightness in these
threaded joints, or to lack of perfect seating
in the valve which controls the auxiliary
duct; and, in view of the very serious im-
portance attached to leakage past the aux-
iliary valve, it is essential, when such leak-
age is observed, to ascertain whether it is
due to the valve, or to the screw threads;
and in such constructions it is necessary to
exhaust the system and get access through
the main body to the auxiliary valve, and to
remove the same for dressing it, or other-
wise getting access to its seat to insure that
no leakage can occur past this valve. In a
large percentage of instances in which this
elaborate and laborious attention is neces-
sary in such constructions, the trouble is not
with the auxiliary valve, but with the screw-
threaded joints, so that if this could have
been assuredly known, the large amount of
repair work and attention would have been
avoided. In the construction herein shown
and described the absence of threaded joints
leading to any source of water for leakage
makes it certain that if leakage is observed,
it occurs by reason of poor seating of the
valve which controls the auxiliary duct, and
no time or labor is therefore liable to be
wasted by reason of uncertainty as to the
cause of leakage.

The main valve and its seat, including the
auxiliary valve and its seat, being constructed
as a unitary structure which may be
separated from between the main valve body
and the water inlet pipe terminal, all work
upon either valve, or upon the peripheral
clamping areas of the valve seat member,
can be done at the bench, where perfectly
convenient access can be had to the parts
requiring attention; and no work of this
sort has to be done through the main valve
hand-hole 18, as is unavoidable in many con-
structions of this general type.

In Figure 3 there is shown a detail modifi-
cation consisting in that the main valve seat
member, 16^x, interposed and clamped be-
tween the supply pipe terminal, 11^x, and the
main valve body, is dimensioned diametri-
cally only for comprising the main inlet
valve seat, and said peripheral flange for
clamping between the other two members
mentioned, and is not dimensioned for con-
taining the auxiliary duct except as to the
inlet end thereof seen at 30^y, the remainder
of said auxiliary duct being formed as seen
at 30^x through the flange, 11^a, of the supply
pipe terminal, 11^x. In this construction the
requirement that all connections leading

from any water space shall contain no 65
threaded joint, is met, and said duct is
made non-leaking at any point in its extent
between the seat of the valve which con-
trols it and the outside of the valve body,
by the clamping of the valve seat member 70
16^x between the two adjacent parts of the
structure, which clamping clamps the mem-
ber 16^x securely water-tight at the point at
which the duct terminal 30^y therethrough
registers with the remainder of the duct 30^x 75
in the flange of the supply pipe terminal.

I claim:

1. In a construction of the class indicated
a main valve body and an immediately ante-
cedent water pipe element on which said 80
valve body is mounted at the intake of the
latter; a valve seat member peripherally di-
mensioned for clamping engagement between
the facing surfaces of said valve body and
pipe element marginal with respect to the 85
registering apertures of said parts; and
means for securing the valve body and pipe
element together adapted for clamping said
valve seat between said marginal areas, said
valve seat member being dimensioned as to 90
thickness for exposing a substantial width of
peripheral area outwardly between the two
members between which it is clamped, said
valve seat member having formed in it an
auxiliary duct opening at the inner end in 95
the direction toward the seating movement
of the main valve and opening at the outer
end through the exposed periphery of said
valve seating member, and a valve carried
by the main valve for controlling the inner 100
end of said duct.

2. In a construction of the class indicated
a main valve body and an immediately ante-
cedent water pipe element on which said 105
valve body is mounted at the intake of the
latter; a valve seat member peripherally di-
mensioned for clamping engagement be-
tween the facing surfaces of said valve body
and pipe element marginal with respect to 110
the registering apertures of said parts; and
means for securing the valve body and pipe
element together for clamping said valve
seat member between said marginal areas;
an auxiliary duct leading from the inner side
of said valve seat member, extending past 115
the marginal seat of the valve seat member
on the water inlet member, and terminating
for discharge through an exteriorly-exposed
area of one of said two last mentioned mem-
bers; and a valve operated by the main valve 120
for opening and closing simultaneously
therewith for controlling water access to said
auxiliary duct.

In testimony whereof, I have hereunto set
my hand at Chicago, Ill., this 26th day of 125
January, 1924.

EMIL TYDEN.
